UNITED STATES PATENT OFFICE.

HARRISON J. L. FRANK, OF DETROIT, MICHIGAN, ASSIGNOR TO MUTUAL ELECTRIC AND MACHINE COMPANY, OF DETROIT, MICHIGAN, A CORPORATION OF WEST VIRGINIA.

SWITCH.

Application filed May 5, 1922. Serial No. 558,791.

To all whom it may concern:

Be it known that I, HARRISON J. L. FRANK, a citizen of the United States, and residing at Detroit, in the county of Wayne 5 and State of Michigan, have invented a new and Improved Switch, of which the following is a specification.

This invention relates to switches having stationary terminals in pairs and pivoted 10 contact arms adapted to bridge across between the terminals, and especially to that class of switches in which the actuating member connects to the contact arms by means of a spring which is subject to considerable tension before the arms move, resulting in a rapid movement of the arms to engage and disengage the contacts and terminals, and the object of this present invention is not only to provide simple and efficient 15 resilient mechanism for actuating the contact arms, but also to provide a positive connection between the actuator and the contact arms by means of which the arms are positively forced to disengage the terminals should the adherence between them be too great for the spring to overcome. Another object of this invention is to mount a coil spring directly on the positive connector between the actuator and the contact 20 arms so that should the spring break, its ends cannot become entangled in current carrying parts of the switch. A further object of the invention is to provide a switch which can be constructed at low cost and 25 in which the various parts are assembled on a rigid frame so that the switch can be mounted as a unit on an insulating base.

This invention is embodied in a switch shown in the accompanying drawing and is particularly pointed out in the claims.

In the accompanying drawing, Fig. 1 is a plan and Fig. 2 is a side elevation of this improved switch. Fig. 3 is a view similar to Fig. 2 with the contacts moved to open position. Figs. 4 and 5 are sections on the line 4—4 of Fig. 1 showing the actuator in two different positions. Fig. 6 is a section on the line 6—6 of Fig. 2.

Similar reference characters refer to like parts throughout the several views.

The frame of this switch is formed of stiff sheet metal to constitute the feet, sides 55 2 and top 3. Lips 4 may be struck up from the sides and bent up to lie flat with the top 3 to form a broader surface to secure the

switch to a support or to receive a finishing plate.

The actuator consists of a metal yoke of any desired construction formed with the sides 5 which lie between the sides 2 of the base and may have short pivots 6 at their lower ends mounted in proper holes in the sides 2 of the frame, a top 7, and a small transverse member 8 extending between the sides 5. Any desired means may be employed to swing the actuator in its pivots 6, the device shown being a handle 9 of any suitable material such as fibre, gutta-percha or similar substances, or metal if desired, which handle may be provided with segmental arms 10 which close the opening 12 in the top 2 through which the handle 9 extends. The handle need not be central of the actuator unless so desired.

The contact carrier consists of two sides 14 outside of the sides 2 of the base, a bottom 15 having an ear 16 pressed upwards, and, if desired, two arms 17 having down-turned ends 18. Where width is not desired, the arms 17 may be omitted and the contacts secured directly to the sides 14 or suitably spaced therefrom. A connector 19 at its lower end hooks into the ear 16 and with its hook-shaped upper end it connects to the cross member 8 of the actuator, although it may be reversed if desired, or given any other form which will permit a slidable connection with one of the main members within fixed limits. The spring 20 connects to this part 8 and to the lower end 90 of the link 19. If the lower end of the spring connected to the ear 16, the link would rattle at each actuation of the switch, although this would not prevent the switch from operating properly and such mounting of the spring may be adopted if desired. The sides 14 are mounted on the pivots 22 carried by the sides 2 which are some distance above the pivots 6 of the actuator. It is to be understood that in all cases the pivots may be attached to the moving member. The sides 2 are formed with notches 23 to permit the contact carrier to swing in its pivots, the metal at the ends of these notches acting as stops for the carrier.

This switch has a pair of terminals 25 on each side which are entirely independent of each other. The knife-shaped terminals have feet 24 extending inwardly below the feet of the frame and insulated therefrom 110

by the squares 26 which are held in position by the flanges 27 formed in those feet. A plate 28 of insulation extends between the feet on each side of the frame and metal eyelets 29 may be used to secure the parts together.

Secured to the down-turned ends 18 of the contact carrier are pairs of arms 31, each preferably formed of two leaves held together at their middle portions by means of the ends 18, plates 32 of insulating material, metal plates 33 and rivets 34. Opposite edges 35 of the ends of these arms 31 are flared out to permit ready entrance of the terminals 25 between the two members which constitute the arms as shown in Fig. 1, edges of the terminals being made sharp to assist in this entrance.

When the parts are as shown in Figs. 1, 2 and 4, the ends of the contact arms receive the terminals and the parts are held in this position by the friction between the terminals and contact arms and the pull of the spring 20. When the actuator is moved to the position shown in Fig. 5, tension is placed on the spring but no movement of the contact carrier occurs until the line between the shaft 8 and the ear 16 has passed some distance to the left of the pivot 22, at which time a turning pull is exerted by the spring 20 on the contact carrier. When this pull is sufficient to overcome the "stick" between the arms and the terminals, the arms will be snapped over to the position shown in Fig. 3 by this spring 20.

In a similar manner, when the actuator is moved from the position shown in Fig. 3 to that shown in Fig. 4, there is a delayed movement of the contact carrier until the line of the spring moves across the pin 22 and the tension on the spring is sufficient to overcome the friction. At that instant the spring will snap the contact carrier to the position shown in Figs. 2 and 5. This structure is therefore a quick-make and quick-break switch. It will be noted that this snap does not occur until the line of the spring passes the pivot 22 for the contact carrier and that by that time, the spring is well tensioned.

It sometimes happens that small areas of the arms and terminals are electrically welded together or that they are stuck together for other reasons to such a degree that the spring 20 is not sufficiently strong to separate them. I therefore provide the link 19 which normally is inoperative, but which forms a positive operative connection between the pin 8 and the ear 16 and begins to pull the lower part 15 of the contact carrier to the left in Fig. 5 when the actuator reaches the position indicated in dotted lines in this Fig. 5. This pull may become sufficiently great to disengage the contacts at the ends of the arms and the terminals, after

which the spring will snap to the limit of their travel.

By positioning the pivot 6 of the actuator somewhat to the left of the central line of the switch, as shown in Fig. 2, the action of the spring in swinging the contact arms from the position shown in Fig. 2 to that shown in Fig. 3 is much stronger and faster than when moving the arms in the opposite direction. This causes the movement of these arms while disengaging the terminals to be very fast and substantially avoids arcing.

This positive connection between the actuator and the contact carrier may be used in many other types of snap switches and I do not wish to be limited to the use of the contact arms and terminals nor to the finger 9 shown in the drawings. The details and proportions may all be changed by those skilled in the electric arts without departing from the spirit of my invention as set forth in the following claims.

I claim:—

1. In a switch, the combination of a frame having spaced sides, a contact carrier pivoted on the frame and comprising sides outside the frame and a cross member connecting the sides, an actuator pivoted within the frame adjacent the path of said cross member, resilient and positive connectors between said contact carrier and the actuator, a pair of stationary contacts mounted on the frame, and a pair of contacts mounted on the contact carrier adapted to engage and disengage the stationary contacts as the contact carrier is moved by the actuator.

2. In a switch, the combination of a frame having spaced sides, a contact carrier pivoted on the frame and comprising sides outside the frame and a cross member connecting the sides, an actuator pivoted within the frame adjacent the path of said cross member, a pair of stationary contacts mounted on each side of the frame, a pair of contacts mounted on the contact carrier at each side of the frame adapted to engage and disengage the stationary contacts, and resilient and positive connectors between said cross member of the contact carrier and the actuator and within said frame whereby movements of the actuator may cause engagement and disengagement of said contacts.

3. In a switch, the combination of a support and a contact thereon, a contact carrier pivoted on the frame and a contact on said carrier, an actuator pivoted on the frame a distance from the pivot for the contact carrier, a coil spring and a link within the spring connecting at their ends to the contact carrier and actuator a distance from their respective pivots, the ends of the spring and link attached to the actuator and adapted to be moved to tension the spring

until the line of the spring passes over the pivot for the contact carrier to cause the spring to snap the contacts into and out of engagement.

- 5 4. In a switch, a stationary contact, a pivoted contact carrier and a contact mounted thereon and adapted to engage the stationary contact, an actuator pivoted a distance from the pivot for the contact carrier, a coil
 10 spring connecting at its ends to the contact carrier and actuator and adapted to be tensioned by the actuator until the line of the spring passes over the pivot for the contact carrier to cause the spring to snap the contacts into and out of engagement, and a link within the spring connecting the carrier and actuator and having a slidable connection with one of them to positively cause the contacts to engage or disengage
 15 20 when the spring fails to function for that purpose.

5. In a quick-make, quick-break mechanism, a pivoted operated member adapted to spring back and forth between predetermined limits, an actuator pivoted a distance from the pivot of said operated member, and a coil spring and a link within the spring connecting the actuating member and the operated member and adapted to be moved across the line connecting the pivots of said members, said spring being thereby tensioned to swing the operated member in either direction, and said link serving to positively swing the operated member in either direction when said spring is inoperative for such purpose.

6. In a quick-make, quick-break mechanism, a pivoted operated member adapted to spring back and forth between predetermined limits, an actuator pivoted a distance from the pivot of said operated member, and a spring and link connecting the actuator

ing member and the operated member and adapted to be moved across the line connecting the pivots of said members, said spring being thereby tensioned to swing the operated member in either direction, the angular distance traveled by said operated member from the line connecting said pivots being greater in one direction than in the other.

7. In a quick-make, quick-break mechanism, a pivoted operated member adapted to spring back and forth between predetermined limits, an actuator pivoted a distance from the pivot of said operated member, and a spring and link connecting the actuating member and the operated member and adapted to be moved across the line connecting the pivots of said members, said spring being thereby tensioned to swing the operated member in either direction, and the rate of movement of the operated member under the action of said spring being greater in one direction than in the other.

8. In a quick-make, quick-break switch, a stationary contact, a pivoted contact carrier adapted to swing back and forth between predetermined limits, a contact thereon adapted to be carried into and out of engagement with said stationary contact, an actuator pivoted a distance from the pivot for said contact carrier, and a spring and link connecting the actuator and the contact carrier and adapted to be moved across the line connecting the pivots of said members, said spring being thereby tensioned to swing the contact carrier in either direction, the rate of movement of the contact carrier under the action of the spring being greater when the contacts are disengaged than when they are caused to engage.

HARRISON J. L. FRANK.
